Attorney,

UNITED STATES PATENT OFFICE.

ROSS HAZELRIGG, OF OAKLAND, CALIFORNIA, ASSIGNOR TO VACO MANUFACTURING CO., A CORPORATION OF CALIFORNIA.

VACUUM SUPPORTING DEVICE.

1,026,263.

Specification of Letters Patent.

Patented May 14, 1912.

Application filed July 15, 1909, Serial No. 507,844. Renewed October 9, 1911. Serial No. 653,724.

To all whom it may concern:

Be it known that I, Ross HAZELRIGG, citizen of the United States, residing at Oakland, in the county of Alameda and State of California, have invented certain new and useful Improvements in Vacuum Supporting Devices, of which the following is a specification, reference being had therein to the accompanying drawing.

10. This invention relates to vacuum supporting devices of the type set forth in my application filed March 6, 1909, Serial No. 481,855, wherein spring arms project from the vacuum cup and contact with the surface to which the cup is attached, to both increase the suction space of the cup and provide means for suspending articles.

The principal object of the invention is to simplify the type of spring arms employed and also to provide an interlocking engagement between the head of the cup and the arms so that there will be no danger of slippage of said arms relative to said head.

In carrying out the objects of the invention generally stated above it will, of course, be readily understood that the essential features thereof are necessarily susceptible of changes in details and structural arrangements, but certain preferred and practical 30 embodiments of the same are shown in the accompanying drawings wherein—

Figure 1 is a view in front elevation of the improved vacuum supporting device attached to a supporting surface. Fig. 2 is a 35 central vertical sectional view taken on the line 2—2, Fig. 1. Fig. 3 is a view similar to Fig. 1, but showing a modified form of the invention. Fig. 4 is a fragmentary vertical sectional view taken substantially on the line 4—4, Fig. 3. Fig. 5 is a detail perspective view of the arms used in the modified form of the invention.

Referring to said drawings by numerals, 1 designates the wall or other surface to which 45 the improved vacuum supporting device is attached. Said device comprises the usual cup-shaped body 2. Said body 2 is provided with an enlarged outstanding and preferably rounded head 3 which forms a hand-grip by means of which the attaching or detaching of the body to its supporting surface is facilitated.

The cup and head are integral and are

formed of rubber molded to the desired shape and in the process of molding the same a wire is embedded within the head, said wire being provided with a central arched portion 4 which provides the necessary interlocking engagement between the head 3 and the wire. An arm projects from each end of said arch, said arms being designated by the numerals 5 and 6. The arms project beyond the outer edge of the cup and are curved so that their ends will be in position to contact with the surface to which the cup is attached and through their resiliency, distend the said cup and thereby increase its suction space, as is set forth in the aforesaid application. The arm 5 has its end outturned as indicated at 7 so that it 70 may be used in a manner similar to card racks, and the arm 6 has its end in the form of a hook 8 upon which articles may be suspended.

In the modified form of the invention shown in Figs. 3, 4 and 5, two wires are embedded within the head of the cup, the arches 9 and 10 of said wires crossing within the said head. The arms 11—12 and 13—14 are similar to the arms 5 and 6, but owing to the crossing relation of their central arches, they radiate from the head of the cup and thereby provide two suspending hooks and two outturned ends for cards and the like. Preferably the wire used is large piano-wire 85 as the same is both strong and resilient.

It will be seen from the foregoing that as the wires are molded within the heads of the cup and are held therein by means of their central arch, the finished article will 90 be both strong and serviceable.

What I claim as my invention is—

As a new article of manufacture, a vacuum cup, and resilient arms projecting from said cup and adapted to contact with the surface to which the cup is attached, to increase the suction space thereof, said arms having an arch-shaped connecting portion embedded within said cup.

In testimony whereof I hereunto affix my signature in presence of two witnesses.

ROSS HAZELRIGG.
